CLAIM

The ornamental design for a kayak rack, as shown and described.

DESCRIPTION

FIG. 1 is a front-top-right view of a kayak rack showing my new design in a deployed configuration;

FIG. 2 is a rear-bottom-left view thereof;

FIG. 3 is a front elevational view thereof;

FIG. 4 is a rear elevational view thereof;

FIG. 5 is a left elevational view thereof;

FIG. 6 is a right elevational view thereof;

FIG. 7 is a top plan view thereof;

FIG. 8 is a bottom plan view thereof;

FIG. 9 is a front-top-left perspective view of kayak rack in collapsed configuration;

FIG. 10 is a rear-bottom-right perspective view thereof; and, FIG. 11 is a top perspective view of kayak rack in a deployed configuration on a vehicle.

The broken lines showing hinges, fasteners, and other features in FIG. 1 through 11 are included for the purpose of showing environmental structure and form no part of the claimed design.

The broken line showing a vehicle in FIG. 11 are included for the purpose of showing environmental structure and form no part of the claimed design.

1 Claim, 11 Drawing Sheets
